(57) **CLAIM**

I claim the ornamental design for a bottle, as shown and described.

DESCRIPTION

FIG. 1 is a top, front, and left side perspective view of a bottle, showing my new design;

FIG. 2 is a bottom plan view thereof;

FIG. 3 is a top plan view thereof;

FIG. 4 is a front elevational view thereof, the rear elevational view being identical; and,

FIG. 5 is a corner elevational view thereof, the opposite corner elevational view being identical.
